Inventor: Scott J. Harris,
By Thomas G. Orwig, Attorney.

UNITED STATES PATENT OFFICE.

SCOTT J. HARRIS, OF ORTONVILLE, IOWA.

DOUBLE-ACTION FORCE-PUMP.

SPECIFICATION forming part of Letters Patent No. 460,964, dated October 13, 1891.

Application filed May 1, 1891. Serial No. 391,243. (No model.)

To all whom it may concern:

Be it known that I, SCOTT J. HARRIS, a citizen of the United States of America, residing at Ortonville, in the county of Dallas and

5 State of Iowa, have invented a new and useful Double-Action Force-Pump, of which the following is a specification.

My object is to provide means for forcing a continuous stream of water through a well-tube and also of providing a cheap and convenient supporting-post for the well-tube and the operative parts on the outside of the well-tube; and my invention consists in the construction and combination of a supporting-post having a lever or handle fulcrumed in its top and a submerged force-pump having two sets of valves and two pistons which are alternately reciprocated, as required to force a continuous stream of water through the well-tube and pump-spout connected therewith, by means of connecting-rods which are attached to the pistons and to the pump-handle on opposite sides of the supporting-posts in such a manner as to elevate one connecting-rod, piston, and set of valves while the other connecting-rod, piston, and set of valves is being lowered, as hereinafter more fully described, pointed out in my claim, and illustrated in the accompanying drawings, in 30 which—

Figure 1 is an enlarged detail view of the submerged part of the pump, showing the construction, arrangement, and combination of the pistons and valves with the connecting-rods and other parts. Fig. 2 is a front elevation of the complete device placed in a well as required for practical use; and Fig. 3 is a side elevation of the complete device, taken from a point at right angles from Fig. 2.

40 A is a base, preferably made of cast metal, complete in one piece and adapted to allow a supporting-post to be fixed thereto.

B is a supporting-post, preferably made of tubular iron and attached to the base A by 45 means of a screw on its lower end that enters a screw-threaded bore in the base A. It is adapted to support a well-tube and has at its top perforated projections adapted to allow a pump-handle to be fulcrumed thereto.

50 C is a pump-handle of common form fulcrumed in the top of the supporting-post B.

D is a well-tube attached to the supporting-

post and curved at its top, as required, to form a spout D², and its lower end has branches D³, as required, to connect it with the two valve-chambers, as shown in Fig. 1.

55 F are valve-chambers made in two parts. They are connected to the branches D³ and are adapted to allow spherical balls F² to operate therein, and their lower sections are so shaped as to produce valve-seats F³ for the ball-valves.

H are open-ended cylinders connected with the lower ends of the valve-chambers F. Their lower ends are slotted, as required, to 60 allow piston-rods to be connected with pistons therein.

J are open-ended pump-pistons on the inside of the cylinders H. They are cylindrical in shape, and attached to their tops in a common way are check-valves J².

K are stirrup-shaped piston-rods attached to the lower ends of the piston J. They operate on the outside of the cylinders H and valve-chamber F and traverse the slots in the 75 ends of the cylinders H.

L are connecting-rods attached to the pump-handle G on opposite sides of its fulcrum and to the piston-rods K to impart reciprocating motions to the pistons J and thereby alternately open the check-valves J², attached thereto, when the handle C is operated, as required, to force a continuous stream of water up through the valve-chambers F and the well-tube D and its spout D².

80 It is believed from the foregoing detailed description of the construction and function of the various parts which comprise my invention that the construction and operation of the whole device will be readily understood 90 by any one skilled in the art to which it pertains.

What I claim as my invention, and desire to secure by Letters Patent, is—

An improved double-action force-pump 95 comprising a base, a supporting-post, and a handle fulcrumed therein, substantially as described, a well-tube attached to the supporting-post and curved at the top, as represented, to form a spout, a branch having two arms 100 extending in opposite directions and having a screw-threaded connection with the said tube, two ball-valve chambers formed complete in themselves and having screw-thread-

ed connections with the said branches, open-ended cylinders provided with vertical slots at their lower ends and detachably connected with the said valve-chambers, pistons having their lower ends open and a check-valve at their tops placed in the said open-ended cylinders and adapted to be vertically reciprocated therein, and piston-rods connected with the handle on opposite sides of its fulcrum

and having approximately stirrup-shaped devices on their lower ends which are extended through the vertical slots in the said cylinders and attached to the valve-bearing pistons, substantially as shown and described.

SCOTT J. HARRIS.
